LOADER CONVEYER

William Hurst Lewis, Altadena, Calif., assignor
to Standard Steel Corporation, Los Angeles,
Calif., a corporation of California

Application April 18, 1945, Serial No. 589,049

4 Claims. (Cl. 198—164)

1

My invention relates to a loader.

One of the principal objects of this invention is to provide a structure which is particularly adapted for conveying relatively larger quantities of such materials as sand, aggregates, rock, or the like, at relatively steep inclines, thus, particularly adapting the structure to a loader for transferring such materials.

Another important object of this invention is to provide a structure of this class having a conveyor whereby objects of various and large size may be effectively transported, and which will automatically reject objects too large to be carried or which will yield to large objects which are not in the desired or proper positions to be carried.

An important object also of this invention is the provision of a novelly and simply constructed conveyor for carrying out the purposes of the foregoing objects.

A further important object of this invention is the provision of a structure of this class comprising a belt conveyor, having a relatively steep inclined stretch and also stretches of less or other inclination, and a flight conveyor in association with the relatively steep inclined portion or stretch of the belt conveyor, thereby both simplifying the conveyor construction and providing an effective and efficient loader, particularly for loading trucks, and the like, from the ground.

With these and other objects in view, as will appear hereinafter, I have devised a novel loader and conveyor construction as will be hereinafter described in detail and particularly set forth in the appended claims, reference being had to the accompanying drawings and to the characters of reference thereon, which form a part of this application, in which:

Fig. 1 is a fragmentary plan view of a loader incorporating my invention;

Fig. 2 is a fragmentary elevation of the front end thereof, taken at 2—2 of Fig. 1;

Fig. 3 is a sectional elevation thereof taken through 3—3 of Fig. 1;

Fig. 4 is a fragmentary side elevation of the loader shown in Fig. 1;

Fig. 5 is a diagrammatic side elevation of a slightly modified form of construction of the front or feed end of the conveyor;

Fig. 6 is a diagrammatic side elevation of a slightly modified form of the flights of the upper or flight conveyor;

Fig. 7 is an enlarged sectional view taken through 7—7 of Fig. 4 showing the relation between both conveyors;

2

Fig. 8 is a fragmentary sectional view taken through 8—8 of Fig. 8;

Fig. 9 is a fragmentary side elevation of my loader in a modified form of construction; and,

Fig. 10 is a fragmentary side elevation of the upper portion of the loader shown in Fig. 9.

The loader shown in Figs. 1, 4, and 9 is carried on a frame 1 having supporting wheels 2 preferably at one end only, that is, at the rear end. The forward end is designed to be supported and guided by a tractor vehicle (not shown), or other suitable means, the frame 1 having a draw bar or means 1^a to be connected to the tractor hitch of the tractor.

On and within the frame 1 is floatingly positioned a conveyor carrying frame 3 which is shaped substantially as a right triangle, the lower portion of the rear end 3^a being mounted on the axle 1^b of the frame 1, this rear end extending vertically and high above the base 3^b, and the forward end 3^c being low and extending substantially to the ground. On the inclined or hypotenuse side 3^d of the frame 3 is arranged the conveying means consisting of the conveyors 4 and 5.

The conveyor 4 is a continuous wide belt having transverse straps 6 at its under or inner side, the ends of which straps are carried by continuous laterally spaced apart chains 7 which extend over pairs of spaced sprockets 8 and 9, located, respectively, at the upper and lower ends of the inclined portion 3^d of the frame. The upper runs of the chains are carried on tracks 10 mounted on structural channels 11 on the inclined portion 3^d of the frame 3.

On the shaft, carrying the upper sprocket 8, is a driven sprocket 12 which is driven by a chain 13 from a drive sprocket 14 on the transmission mechanism 15 of the motor 16 mounted on the base 3^b of the frame 3.

The upper run 4^a of the belt conveyor 4 forms a moving bottom of a material directing trough A along the inclined portion 3^d of the frame 3. The sides of the trough are provided by plates 17 which are carried by the frame 3 and diverge upwardly from the opposite edges of the upper run of the belt 4. To the lower edges of the plates are secured flexible tongues or flaps 18, the upper portions thereof being secured to the backsides of the plates 17 and the lower edge portions overly the belt 4 inwardly from the edges.

The conveyor 5 is a flight conveyor consisting essentially of flights 5^a of metal plates. These flights have hinge portions 5^b which pivotally support the flight plates on rods 21 positioned at the inner edges of the flight plates. These rods

extend transversely of the conveyor and are secured at their ends to brackets 22 carried at the inner sides of a pair of laterally spaced continuous chains 23. The lower and upper runs of these chains are carried on tracks 24 on the opposite sides of upper inclined portion 3^d of the frame 3. The lower runs of the chains 23 are held against the tracks 24 by guide plates 25.

The brackets 22 have extensions 22^a which extend outwardly from the chains in front of the flight plates and yieldable hold the same at right angles to the chains. Thru the extensions and flight plates extend tension members or bolts 26. Each bolt carries a compression spring 27 between the back side of the plate and a nut 26^a at the inner end of the bolt. Thus, as the lower run of the conveyor 5 moves upwardly with the upper run 4^a of the belt conveyor, and too large or heavy an object, such as a rock, lodges in front of the flight plate, it may yield sufficiently to reject or pass such object.

The free edges of the flight plates 5^a of the lower run of the conveyor 5 move contiguous to and substantially with the upper run 4^a of the belt conveyor, and the lateral edges of the flight plates 5^a are positioned contiguous to the side wall plates 17.

The chains 23 are carried at the upper and lower ends on sprockets 28 and 29, mounted on the frame 3.

On the opposite end of the shaft from the sprocket 12 is a gear 31 which meshes with an idler gear 32. This gear 32 drives a coaxial sprocket 33 which drives, through a chain 34, a sprocket 35, mounted on the shaft carrying the upper or drive sprockets 28 for the flight conveyor 5. In this manner the conveyors 4 and 5 are synchronized, so that their adjacent or contiguous runs move in substantial unison.

Means are provided at the lower forward end of the frame 3 for adjusting the conveyors 4 and 5, such as the slides 41 and 42 which carry the sprockets 9 and 29, there being shown screws 43 and 44 to facilitate such adjustment.

At the lower end of the frame 3 is provided an angular plate 51 for directing the materials to be transferred by the loader onto the front end of the belt conveyor 4. At each end of the plate 51 are provided plates 52 which diverge forwardly to facilitate the direction of material to the belt conveyor 4.

The forward end of the frame 3, and therefore of the plate 51, may be raised or lowered as desired further to facilitate the movement of the materials onto the conveyor 4, such as by means of the hydraulic lift 36.

In the modified structure, shown in Fig. 5, the lower forward ends of the chains 23 of the flight conveyor 5 extend over pairs of sprockets 61 and 62, so as to provide an additional short run 5^b, which is directed slightly downwardly, in order to force the material to be loaded up the plate 51 onto the belt conveyor 4.

In the modified structure shown in Fig. 6 the flight plates, designated 71, are slightly cupped to facilitate conveyance of the material carried on the belt conveyor 4.

In the modified structure shown in Figs. 9 and 10, the loader has an overhead extension for extending the discharge end for more effectively loading a truck, designated E. Such extension is provided on an overhanging arm or cantilever beam 81 at the upper end of a right-angle-shaped conveyor supporting frame, designated 82. The upper run of the belt conveyor, in

this instance and designated 83, has a relatively steep inclined stretch 83^a and a less inclined or substantially flat stretch 83^b extending beyond the upper end of the steep or more greatly inclined stretch 83^a. The stretch 83^b is carried on the overhanging arm 81. The flight conveyor 84 is positioned only above the steep inclined stretch 83^a of the upper run.

Between the ends of the belt conveyor 83 are idlers 85 and 86 for changing directions between the more greatly inclined stretch 83^a and the upper less inclined stretch 83^b.

In this instance the upper end of the flight conveyor has a sprocket 87 which is driven directly by a chain 88 from the motor 16 similarly mounted on the frame 82. Through gears 89 and 90, the sprocket 87 drives a sprocket 91 which drives, through a chain 92, a sprocket 93, at the extended end of the overhanging arm 81. This sprocket 93 is coaxial with sprockets 94 around which extend the chains carrying the belt conveyor 83.

Though I have shown and described a particular construction, combination and arrangement of parts and portions, and certain modifications thereof, I do not wish to be limited to the same, but desire to include in the scope of my invention, the construction, combination, and arrangement, substantially as set forth in the appended claims.

I claim:

1. In a machine of the class described, a conveyor comprising a pair of spaced chains, flights pivotally carried at their opposite ends by the chains and extending outwardly therefrom, brackets also carried by the chains in association with and in front of each of the flights, bolts extending from the brackets, thru and behind the flights, and compression springs between the back sides of the flights and the latter ends of the bolts.

2. In a machine of the class described, a conveyor comprising a pair of spaced chains, a plurality of rods positioned transversely of the conveyor and connected at their ends to the chains, brackets carried by the chains at the ends of the rods, flights pivotally mounted on the rods behind the brackets, bolts extending from the brackets, thru and behind the flights, and compression springs between the backsides of the flights and the latter ends of the bolts.

3. In a loader of the class described, a frame, a belt conveyor mounted thereon, a flight conveyor mounted above the belt conveyor with the flights of the lower run extending toward and positioned contiguous to the upper run of the belt conveyor, the frame having a trough, the side walls of which extend upwardly from the upper run of the belt conveyor, the lateral ends of the flights terminating adjacent said side walls, the bottom of the trough being formed by the upper run of the latter, and means comprising yieldable portions on the lower edges of the side walls, engaging the lateral portions of the upper run of the belt conveyor, substantially sealing the side walls with the upper run of the conveyor belt, but only to the extent of allowing the belt conveyor to operate.

4. In a loader of the class described, a frame, a belt conveyor mounted thereon, a flight conveyor mounted above the belt conveyor with the flights of the lower run extending toward and positioned contiguous to the upper run of the belt conveyor, the frame having a trough, the side walls of which diverge upwardly from the edges of the upper run of the belt conveyor, the lateral ends of the flights terminating adjacent said side

walls, the bottom of the trough being formed by the upper run of the latter, and means comprising yieldable portions on the lower edges of the side walls, engaging the lateral portions of the upper run of the belt conveyor, substantially sealing the side walls with the upper run of the conveyor belt, but only to the extent of allowing the belt conveyor to operate.

WILLIAM HURST LEWIS.
